JOSEPH JOHN HOLSEN, OF MANITOWOC, WISCONSIN.

WATCH-CHARM.

1,107,950.

Specification of Letters Patent. Patented Aug. 18, 1914.

Application filed August 22, 1913. Serial No. 786,144.

To all whom it may concern:

Be it known that I, JOSEPH JOHN HOLSEN, a citizen of the United States, residing at Manitowoc, in the county of Manitowoc and State of Wisconsin, have invented a new and useful Watch-Charm, of which the following is a specification.

This invention has reference to improvements in watch charms, and is designed to provide a charm so constructed that while it may be carried upon the watch chain, is operable in a useful manner to serve various purposes.

In accordance with the present invention the device comprises two similar members pivoted together at one end and formed of flat material so that they may move one upon the other in substantially parallel planes, and the two members are provided with a marginal portion or rim so related to the members as to permit the stated movement, but constraining the members to one extreme of movement. The marginal member is made of elastic material, so that the movement of the members in one direction is in opposition to the normal tendency of the border member, and as soon as pressure upon the border member is released the latter will return the other members to their first position.

The two flat members at the ends remote from their pivot connection are provided with uniting and stop members shaped to coact in a manner permitting their use for the extraction of splinters from the flesh, or the picking up or holding of any small articles, and between the two extremes the members are provided with cutting portions so related that the device may be used both as a cigar tip cutter and a nail clipper. Moreover, the border member is so related to the pivoted ends of the flat members that there is provided a space for the attachment of the device to a watch chain, so that it may hang pendently therefrom in the manner of a watch charm and by suitable ornamentation the device may provide a pleasing as well as a useful one.

The invention will be best understood from a consideration of the following detailed description, taken in connection with the accompanying drawings forming a part of this specification, with the further understanding that while the drawings show a practical form of the invention, the latter is not confined to any strict conformity with

the showing of the drawings, but may be changed and modified so long as such changes and modifications mark no material departure from the salient features of the invention.

In the drawings:—Figure 1 is a plan view of the device viewed from one face. Fig. 2 is a plan view of the device as viewed from the other face of the device with the sides moved partly together. Fig. 3 is a section on the line 3—3 of Fig. 1.

Referring to the drawings, there is shown two plates 1 and 2, respectively, each having one edge or margin elliptically curved and the other edge or margin in part straight, as indicated at 4, and there beveled from one face to form a knife edge, the straight portion 4 including less than the whole length of the plate. Beyond one end of the straight portion 4 each plate is formed with an ear 5 directed toward the other plate and overlapping the corresponding ear, while the two ears are connected by a rivet or pivot pin 6, wherefore the two plates are pivoted together at the end having the ears 5. At the end of the cutting edge 4 remote from the corresponding ear 5 is a lip 7 offstanding from the edge 4 similarly to the direction of projection of the ear 5 therefrom and both the ear 5 and lip 7 project from the edge 4 in a direction away from the elliptically curved edge 3. At the end of each plate 1 and 2 remote from the ear 5 is another lip 8 spaced from the lip 7 and between the two lips 7 and 8 there is a reentrant curved portion 9 beveled at one edge to form the curved portion 9 into a cutting edge, the two cutting edges 9 of the respective plates 1 and 2 being respectively oppositely disposed, so that together they define a space or passage adapted to receive the small end of a cigar, whereby on the approach of the two plates the cutting edges 9 will sever the tip end of a cigar after the manner of an ordinary cigar tip cutter.

The lip 8 of the plate 1 has a tongue 10 formed thereon, and this tongue is returned upon itself so as to embrace that edge of the plate 2 remote from the pivot connection with the plate 1, such edge being indicated at 11. The lip 8 of the plate 2 is formed with a tongue 12 in the plane of the lip 8 and projecting in a direction away from the pivoted end of the plate and terminating in a point 13. The corresponding edges of the

tongues 10 and 12 are shaped to come close together, while the point 13 of the tongue 12 may project slightly beyond the rounded end of the tongue 10, so that the two tongues 5 coact like the active ends of a pair of pincers and form a ready means for grasping and withdrawing splinters from the flesh or holding any small articles.

The edges 4 are related one to the other 10 so as to approach progressively from those ends adjacent to the lips 7 and as the edges 4 are beveled from relatively opposite sides to form coactive cutting edges this part of the device may be employed as a nail clipper or for any cutting purpose to which they 15 are adapted.

The curved edges 3 of the two plates have applied thereto the leg portions of a U-shaped member 14, which latter may be in 20 the form of spring wire of suitable length soldered or otherwise united to the curved edges 3 but provided with a yoke portion 15 spaced away from those parts of the two plates where they are pivoted together by the pivot pin 6, and the two ears 5 may be slightly recessed, as indicated at 16, so as to provide a still greater space between the wire border or marginal member 14 at the yoke portion and 25 the corresponding part of the two plates 1 and 2. This not only permits an approach of the yoke portion of the wire border to the pivoted ends of the plates when they are caused to move one on the other in overlapping relation, but also provides room for the attachment of a ring or other device employed to secure the device to a watch chain as a pendent or charm.

The wire 14, which may be taken as 40 indicative of any spring member, has a normal tendency to separate the plates 1 and 2 in the direction of their width, but the extent of separation is limited by the engagement of the tongues 10 and 12 at which time the wire border member still has an elastic or spring 45 tendency to separate the plates. The border member 14 is yieldable to pressure applied at its leg portions to cause them to approach and such an approaching movement 50 also causes the plates 1 and 2 to slide one on the other for a distance sufficient to cause the edges 9 to completely sever the top of a cigar or to cause the edges 4 to cut anything introduced between them, while the separating action of the spring border member 55 14 upon the plates 1 and 2 will cause the tongues 10 and 12 when brought together to grip any small article between them with sufficient force to hold it, and this is especially true in the case of a splinter which if 60 engaged between the tongues will be held sufficiently tight by the elasticity of the spring border member 14 to permit the withdrawal of the splinter from the flesh.

65 The members 1 and 2 may be made of any

plate material and the border member 14 may be made of round wire or any other spring material of sufficient gage to not only have the spring effect, but to prevent injury or unpleasantness to the fingers of the 70 operator.

The device in its normal inactive position comprises two flat plates pivoted together at one end and at the other having lips in overlapping relation, which lips are formed 75 with stop members, one of which is in embracing relation to the other plate to retain the two plates in contact at said end, the adjacent margins of the plates being provided with coacting shearing edges. The outer edges or margins of the plates have the spring member fast thereto in a manner tending to constantly move the plates apart, but these plates are never separated sufficiently to provide an open end through 80 which anything may be introduced although the cutting or shearing edges are sufficiently separated for the introduction of the article or articles to be cut between them in a direction substantially perpendicular to the 85 planes of the plates.

The term shearing edges is not intended to be restricted to either one of the sets of shearing edges shown in the drawings.

The lips 7 and 8 of one plate are always 90 in overlying relation to the other plate and never move far enough away from the other plate about the hinge connection of the plates to cause one plate to escape from the other, such separating movement being prevented by the stop members or tongues. Consequently the adjacent shearing edges are always held in the most efficient relation and there is no possibility of one catching on the other as they are approached. 105

The device may be made of any suitable shape other than that shown in the drawings, and may be ornamented in any manner desired, but there is no attempt in the drawings to show any type of ornamentation. 110

What is claimed is—

1. A device for the purpose described, comprising two flat plates pivoted together at one end and at the other end having lips 115 in overlapping relation and there formed with stop members, one of which is in embracing relation to the other plate to retain said plates in contact at said end, the adjacent margins of the plates being formed with 120 coacting shearing edges.

2. A device for the purpose described, comprising two flat plates pivoted together at one end and at the other end formed with stop members limiting the movement of the 125 plates one away from the other about their pivot connection, and one stop member embracing the other plate to retain the plates in contact at said end, the adjacent margins of the plates being formed with coacting 130

shearing edges, and a U-shaped spring embracing the outer margins of the plates and tending constantly to hold the plates with the stop members in engagement, said spring 5 having its bowed or yoke end spaced from the pivoted ends of the plates.

3. A device for the purpose described, comprising two flat plates pivoted together at one end and at the other end having lips 10 each in overlapping relation to the other plate, said plates being also formed with stop members limiting the movements of the plates one away from the other about their pivot connection to always retain the lips 15 in overlapping relation to the respective other plates, and one stop member embracing the other plate to retain the plates in

contact at said end, the adjacent margins of the plates being formed with coacting shearing edges, and said plates being joined by a 20 spring member tending constantly to hold the plates with the stop members in engagement, said spring member being of U-shape with the legs fast to the outer margins of the plates and having the yoke portion extending about the pivoted ends of the plates in spaced relation thereto. 25

In testimony that I claim the foregoing as my own, I have hereto affixed my signature in the presence of two witnesses.

JOSEPH JOHN HOLSEN.
